UNITED STATES PATENT OFFICE.

FRANK A. BAILEY, OF TOLEDO, OHIO, ASSIGNOR TO THE DE VILBISS MANUFACTURING COMPANY, OF TOLEDO, OHIO, A CORPORATION OF OHIO.

NOVELTY ARTICLE.

Application filed May 7, 1923. Serial No. 637,078.

To all whom it may concern:

Be it known that I, FRANK A. BAILEY, a citizen of the United States, and a resident of Toledo, in the county of Lucas and 5 State of Ohio, have invented a new and useful Novelty Article, which invention is fully set forth in the following specification.

This invention relates to novelties and particularly to a bed-room night lamp having provision for holding a quantity of perfume, toilet water, medicated liquid or other preparation to be heated by the lamp and to emit a vapor into the room to scent the same.

15 The object of my invention is to provide lamps of this class with certain improved features, one of which features consists in the provision of a free circulation of air through the lamp and around the liquid container to prevent a too high or detrimental heating of the same by the lamp.

The invention is fully described in the following specification, and while, in its broader aspect it is capable of embodiment 25 in numerous forms, a preferred embodiment thereof is illustrated in the accompanying drawings, in which,

Figure 1 is a central longitudinal section of a device embodying the invention with 30 parts in full. Fig. 2 is a top plan view thereof. Fig. 3 is a top plan view of the liquid holding pan, and Fig. 4 is an enlarged fragmentary sectional view of a portion of the article base.

35 Referring to the drawings, 1 designates the base of the article, which base is composed of lower and upper sections 2 and 3, respectively which are of circular form in the present instance, and have their outer 40 or opposite ends flared, the former to form a broad base portion for seating on a support and the latter to form a support for the chimney member 4 of the article. The inner or adjacent ends of the base sections 45 2 and 3 are of substantially the same diametrical size and each formed with an in-turned flange 5 which seat one upon the other and cooperate to form a central vertical opening through the meeting ends of the 50 base sections.

A metallic shell 6 of tubular form and substantially the diameter of the opening through the meeting ends of the base sections is projected at its lower end through 55 such opening and is retained in assembled

relation to the sections by upper and lower integral flanges 7 forming an annular recess 8 into which the inner or free edges of the flanges 5 fit, thereby retaining the base sections in assembled relation and also providing a simple and convenient means for carrying the shell 6 in upright position by the base. A lamp receiving socket 9 for receiving an electric lamp bulb 10 is mounted in the shell 6 and has an electrical cord 11 leading therefrom to adapt the socket to be connected to any suitable source of electrical supply, as well understood in the art.

60 The chimney 4, in the present instance, is of cylindrical form, being open at its top and bottom and has its lower edge seating within an upturned flange 12 at the outer edge of the upper base section 3.

65 A liquid holding pan 13 is mounted in the upper portion of the chimney 4, being suspended therein by the provision of an upper edge flange 14 thereon which rests on the upper end of the chimney. The pan when mounted in the chimney entirely closes the upper end opening thereof and in order to 70 provide ventilation spaces or openings through the pan the upper edge of the pan body is slit at intervals from the flange 14 and the side portions 15 of the pan below the slits are pressed into the pan to provide 75 circulation spaces 16 up through the side portions of the pan or between the pan and chimney at intervals therearound. The bottom of the pan and upper end of the lamp 80 10 are preferably disposed in adjacent relation to facilitate a heating of the former.

85 A cover 17 in the present instance, of bell-form is mounted over the pan 13 and upper end of the chimney 14 and has an edge flange 17^a extending down around the chimney. 90 The cover is provided with ventilating openings 18 in its top portion which, in the present instance, are shown as being arranged in sets disposed to register with the ventilation 95 passages 16 through the pan 13. Air for the 100 purpose of circulation is admitted into the lower end portion of the chimney 4 through openings 19 provided in the base section 3.

105 It is evident that I have provided a simple and efficient lamp which may be used as a night lamp and for which purpose it is preferable to have the chimney 4 of translucent material so that only somber rays are emitted therethrough. The lamp may also be used as a means for heating a liquid or 110

other material so that vapor or scents emitted therefrom by the heating action may enter the room either to provide a pleasing odor therein or for medicinal purposes.

5 I wish it understood that my invention is not limited to any specific construction, arrangement or form of the parts, as it is capable of embodiment in numerous forms without departing from the spirit of the
10 claims.

Having thus described my invention, what I claim as new and desire to secure by Letters Patent is,—

15 1. A lamp of the class described comprising a base, a chimney supported by and rising from the base, heat generating means disposed within the chimney, a pan mounted within the upper portion of the chimney above the heat generating means, and a cover
20 mounted over the pan, provision being made for the circulation of air upward through the chimney and between the pan and chimney and through the cover.

25 2. A lamp of the class described, comprising a base, a lamp socket in the base, an electric lamp in the socket, a chimney mounted on and rising from the base, a pan supported by the chimney within the upper portion

thereof, and a cover mounted over the pan, said pan and cover each having provision 30 for the circulation of air therethrough from the interior of the chimney and provision being made for the entry of air into the lower portion of the chimney.

3. In an article of the class described, a 35 base, an electric lamp socket mounted in the base, an electric lamp mounted in the socket, a chimney mounted on and rising from the base in surrounding relation to the lamp, said base having provision for the entrance 40 of air into the lower portion of the chimney, a pan suspended within the upper portion of the chimney and having a flange resting on the upper end edge of the chimney, said pan having side portions split from the 45 flange and pressed inward to provide passages for the circulation of air from the interior of the chimney above the pan, and a cover mounted over the chimney and enclosing the pan, said cover having air passages 50 in communication with the air passages of the pan.

In testimony whereof I have hereunto signed my name to this specification.

FRANK A. BAILEY.
